UNITED STATES PATENT OFFICE.

STEPHEN M. CASEY, OF SAN FRANCISCO, CALIFORNIA.

DOOR.

Application filed June 12, 1923. Serial No. 644,907.

To all whom it may concern:

Be it known that I, STEPHEN M. CASEY, a citizen of the United States, and a resident of San Francisco, in the county of San Francisco and the State of California, have invented certain new and useful Improvements in Doors, of which the following is a specification.

This invention relates to a door construction provided with a light opening, a pocket having closures in the form of hinged watertables, said pocket being below the light opening and the watertables forming, when in closed position the lower margin of said opening, sashes having respectively transparent panes and screens, with counterbalancing weights for the sash having the pane, and vertical runways on each side of the door for the said weights to work in.

The object of the invention is to provide a door with a transparent panel and with a screen, either of which may be used, the one not in use being, usually, dropped into the pocket. For example in cold or rainy weather the screen may be dropped into the pocket, in good weather the glass portion may be lowered into the pocket and the screen lifted into place.

The invention consists in the novel features of construction hereinafter pointed out, set forth in the claim, and shown in the accompanying drawings in which:—

Figure 1 is a perspective view of a door, partly broken out and in section, both sashes being lifted into upper position to more clearly show the construction of the door.

Figure 2 is a vertical section through the door, a lower portion being broken away.

Figure 3 is a partial side elevation, the door being broken away and shown partly in section to show one of the side runways for a weight.

Figure 4 is a section on the line 4—4 of Figure 3.

Figures 5 and 6 are detail views of a pulley and its mounting.

Figure 7 is a plan view of a watertable hinge.

In the drawings 1 designates the bottom rail, 2 the upper rail, 3 the stiles, one only of which is shown, and 4 the center rails.

These center rails are placed parallel to each other and spaced apart, as will be seen in Figure 1, and panels 5, inner and outer, connect these rails with the bottom rail 1. 55 The rails 4 and the panels 5 form between them a pocket 6 of sufficient size to receive the sashes to be described hereafter.

This pocket is closed, normally, at the top by two hinged watertables 7, the hinges being indicated at 7^a, said watertables interlocking to make them watertight.

The upper rail 2 is grooved on its lower edge as at 8, these grooves forming receivers for the upper edges of sashes 9 and 10, and being of sufficient depth to allow the sashes to be lifted sufficiently to permit lifting of the watertables. Sash 9 is provided with a transparent panel, such as glass, and sash 10, which is lighter in construction, with a screen 10^a. These sashes are held in place by removable side stops 11, and by the grooves 8, and when in operative position, that is raised as in Figure 1, rest on the watertables. The stiles are recessed and the recess closed at the front by a vertical panel 12 forming back of it a vertical runway, in each stile, indicated at 13. Pulleys 14 are placed in the upper portions of the panels 12, and cords 16 run over the pulleys and are connected to weights 17 that work in the runways 13, and to opposite sides of the sash 9. Owing to its light construction the screen sash 10 does not require weights.

In the drawing I have shown both sashes 85 lifted, but in practice one of them would be lowered into the pocket 6. In Figure 2 I have shown in dotted lines the sash 9 so lowered and have dotted the position of the watertable under it in the position it would 90 occupy when swung outwardly to permit lowering or raising of the sash.

The door can be formed in any size desired, and the parts may be of any suitable material.

What I claim is:—

A door having an opening defined by stiles and top, center, and bottom rails, the center rails being spaced apart, solid panels connecting each center rail with the bottom rail to provide a pocket to house sash, a 100 pair of sash adapted to be housed in such

pocket, the upper rail being recessed to receive the upper ends of such sash when the same are raised above the center rails, and a sill hingedly connected to the upper edge of each center rail, said sills adapted to meet centrally above the pocket to each afford a support for the respective sash when the

latter is raised, the meeting edges of the sills interfitting to prevent leakage therethrough and to tend to hold said sills in fixed pocket-closing relation when either sash is in raised position.

10

In testimony whereof I affix my signature.

STEPHEN M. CASEY.
